FIRE EXTINGUISHING APPARATUS

Floyd J. Lee, La Habra, Calif., assignor of one-half to J. Leonard Hull, Los Angeles, Calif.

Application July 21, 1943, Serial No. 495,586

3 Claims. (Cl. 169—32)

This invention relates to a fire extinguishing apparatus of the class in which the contents of the extinguisher are intended to be expelled by gas pressure generated within the apparatus by chemical reaction.

Gas pressure is generated within such extinguishers by chemical reaction between an alkali carbonate, such as sodium bicarbonate, and an acid, such as either sulphuric acid or formic acid. For the proper operation of the fire extinguisher it is necessary that the chemical reactions occur at a proper rate. Furthermore, since these extinguishers are frequently stored for a long period of time before occasion arises for their use, it is necessary that the chemicals employed be stable on storage and also that they be adequately sealed from each other and from the aqueous phase of the extinguisher. It is further necessary that the extinguisher be provided with a simple, reliable, and effective means for mixing the chemicals together and with the aqueous contents of the extinguisher when it is desired to operate the extinguisher.

It is a general object of the present invention to provide a fire extinguishing apparatus which is capable of holding gas-generating chemicals in such a manner that they will not deteriorate in storage, which apparatus contains a very simple, reliable, and effective means for insuring operation of the extinguisher when desired.

In the past, chemical fire extinguishers have been constructed in which either the acid or the alkali carbonate are dissolved in the water of the extinguisher, and the other chemical, i. e., alkali carbonate or acid, held within some frangible container which is intended to be broken to instigate the operation of the extinguisher. I have found that in order to insure reliable operation of the apparatus, both the carbonate and the acid should be sealed off from the aqueous contents of the extinguisher until the intended period of operation. The extinguisher must also include means by which the acid is sealed from the carbonate material.

In accordance with the present invention, a fire extinguishing apparatus is provided which includes a container for holding the chemicals in a moisture-sealed condition, separate from the water of the extinguisher. Said container also includes means by which the acid is maintained separate from the carbonate material.

An important element of the fire extinguishing apparatus of the present invention is present in the means and manner in which gas-generating chemicals are mixed together and with the water

of the extinguisher. It is desirable that the gas pressure be built up suddenly in the extinguisher, and it is also desirable that the chemicals be thoroughly admixed with the water of the extinguisher. These objects are best accomplished by first permitting the acid and carbonate material to contact together within the container of the chemicals while said container is sealed off from the body of the extinguisher. In this way, the generation of gas is instigated before any operation of the extinguisher. The seal of the container of the chemicals separating the chemicals from the body of the extinguisher is designed to be suddenly broken to obtain a rapid injection of the chemicals into the aqueous contents of the container. In this manner, the pressure within the extinguisher is built up more rapidly and more thorough mixing of the chemicals occurs.

10 I have discovered that this opening of the seal of the chemical container can be most reliably accomplished by relying upon the gas pressure generated within the chemical container bursting said seal. Any attempts to cut or otherwise open 15 the chemical container so as to provide communication with the body of the extinguisher by means other than the pressure of the gas generated by the chemicals has proved comparatively unreliable and unsatisfactory in practice. Accordingly, the extinguisher of the present invention is made to include a container for the chemicals, which container is provided with a seal for closing off the chemicals from contact with the contents of the body of the container, which seal is so arranged and constructed that the gas pressure generated within the container may burst the seal and cause a rapid injection of the chemicals into the body of the extinguisher.

An important feature of the present invention 20 resides in the fact that a fire extinguishing unit is provided which contains all of the necessary chemicals and operating mechanism for forming a new and efficient fire extinguishing apparatus by inserting it into the shell of any fire extinguisher. Fire extinguish units which form a part of the present invention are capable of being added to any old fire extinguisher body.

The fire extinguishing apparatus of the present invention will be more completely understood 25 from the following description of the preferred form and example of apparatus embodying the invention. For this purpose, I have described a preferred example of the invention in connection with the accompanying drawing, in which

Figure 1 is an elevation in vertical section;

Figure 2 is a section on the line 2--2 of Figure 1.

Referring to the drawing, the apparatus is there illustrated as comprising an extinguisher body 2 of any usual or preferred form which forms a container for extinguishing fluid. An important feature of the present invention is that any old fire extinguisher body may be employed as a container for the apparatus of the present invention. The fire extinguishing body 2 is indicated as having an outlet nipple 3 for attachment to a hose and a threaded neck 4, to which is attached a cap 5. The fire extinguishing unit 6 of the present invention includes a cylindrical shell 7, which cylindrical shell I have found can be formed quite satisfactorily from plastic materials. In case the shell 7 is formed of plastic material, it may be desirable to line the inside of the shell with wax in order to increase the moisture-proof properties thereof. The bottom of the shell 7 is closed by a disc 8, which is molded to the shell 7 in the operation of producing the shell. The disc 8 may, if desired, be formed of wood. The top of the shell 7 is closed by a top member 9, which is provided with a somewhat narrow flange 10, to which the shell 7 is sealed. The top member 9 is separated from the shell 7 during the operation of molding the shell and is installed in position only after the contents of the shell have been inserted. The seal between the flange 10 and shell 7 is most desirably formed by painting plastic as indicated at 26 over the edge of the shell and adjacent portions of the flange 10. There is thereby provided a moisture-proof seal, which seal, however, is readily susceptible to be broken upon generation of gas pressure within the shell 7. By the construction thus provided, upon generation of gas pressure within the shell 7 the entire top of the shell is adapted to be blown off, opening the top of the shell (which is the bottom of the device in the operating position) to permit rapid ejection of the chemicals into the body of the container 2.

The top 9 is provided with a plurality of pointed set screws 11, by means of which the unit 6 is adapted to be suspended from the neck 4 of the body 2. An adjustment of the position of the pointed screws 11 enable the unit 6 to be suspended within the units having considerable range of diameter of neck openings.

The lower half of the shell 7 is indicated as occupied by a frangible acid container 12, which acid container is preferably formed of hard and brittle wax. The acid container 12 has an outer cylindrical wall 13, an annular bottom wall 14, and an inner cylindrical wall 15, with a top member 16. The inner cylindrical wall 15 defines a central bore, the lower portion of which is occupied by a weight 17. The weight 17 fits slidably within the bore formed by the wall 15, and is provided with a pin 18 at its lower end frictionally engaging an opening 19 in the bottom member 8. The top member 16 of the acid container is likewise formed chiefly of a brittle hard wax, but is provided with a pin-shaped metal insert 20, the function of which is to provide an improved striking surface for the weight 17 to facilitate the breaking of the acid bottle when it is desired to operate the extinguisher. When the extinguisher is inverted from the position shown in Figure 1 to a substantially vertical position, the weight 17 will be released and dropped through the bore provided by the wall 15, striking the cover 16 of the acid bottle. This opera-

tion shatters the cover 16 of the acid bottle and allows the acid to intermix with the carbonate material 21, which fills the upper half of the unit 6. Preferably above the acid bottle, I provide 5 a light cylindrical frame 22 holding a cloth gauze 23 in order to hold the carbonate material from contact with the acid container 12. Within the body 2 of the apparatus there is supplied water or other fluid to be propelled from the extinguisher in operation. Included among liquids which may be used in the extinguisher of the present invention are various types of foam-forming materials.

The fire extinguishing apparatus of the present invention may be stored indefinitely without danger of deterioration, since the chemicals are adequately separated from each other and protected against all deteriorating influences. Whenever it is desired to operate the apparatus, 10 it is merely necessary to invert the apparatus. Only a substantially complete inversion of the apparatus will cause the apparatus to operate, since the pin 18 will frictionally hold the weight 17 from dropping, except in a substantially inverted and vertical position. When the weight is released to fracture the acid bottle, the carbonate and acid first react while separated from the contents of the container 2. The gas is generated until the pressure bursts the seal 26. A 15 time interval in the order of one second only is required for the seal 10 to be burst. Upon bursting of the seal 26, the gas generated causes the extinguisher to start immediately, delivering its contents at high pressure.

35 An important advantage of the extinguisher of the present invention is that it eliminates and makes unessential much of the operating mechanism heretofore included in chemical extinguishers, which operating mechanism always is 40 subject to possible deterioration on standing, rendering the extinguisher unreliable in operation.

While the particular form of fire extinguishing apparatus herein described is well adapted to carry out the objects of the present invention, it 45 is to be understood that the invention is capable of being embodied in many other forms, and the invention is not limited to the specific extinguisher shown, but is of the scope set forth in the accompanying claims.

50 I claim:

1. A fire extinguishing apparatus which comprises a tubular container member having a closure at its upper end, and having a rupturable seal between the closure member and the tubular member, an annular frangible bottle for containing acid within said tube but occupying but a portion of the length of said tube, means above said acid containing bottle to permit carbonate material to be held in said tube above said bottle, a weight slidable through said bottle in bottle-breaking operations, the carbonate material and acid being operative when mixed for generation of sufficient gas pressure to burst said rupturable seal between said tube and said closure member.
- 55 2. A fire extinguishing apparatus which comprises a tubular container member having a closure at its upper end, and having a rupturable seal between the closure member and the tubular member, a frangible bottle for containing acid within said tubular member but occupying but a portion of said tubular member, means within said tubular member to permit carbonate material to be held in a portion of said tubular member and to exclude the same from a portion of said tubular member, and a weight slidable
- 60
- 65
- 70
- 75

through said latter portion in bottle-breaking operations, the carbonate and acid being operative when mixed for generation of sufficient gas pressure to burst said rupturable seal between said tubular member and said closure member.

3. A unit for a fire extinguishing apparatus, said unit including a tubular container member having a closure at its upper end, and having a rupturable seal between the closure member and the tubular member, a frangible bottle for containing acid within said tubular member but occupying but a portion of the length of said tubular member, means within said tubular mem-

ber for holding carbonate material in a portion of said tubular member and for excluding carbonate material from another portion thereof, and a weight slidable through said latter portion in bottle-breaking operations, the carbonate material and acid being operative when mixed for generation of sufficient gas pressure to burst said rupturable seal between said tube and said closure member, said closure member having means for suspending the unit from the neck of a fire extinguisher body.

FLOYD J. LEE.
